UNITED STATES PATENT OFFICE.

ALBERT J. LOEPSINGER, OF PROVIDENCE, RHODE ISLAND, ASSIGNOR TO GENERAL FIRE EXTINGUISHER COMPANY, OF NEW YORK, N. Y., A CORPORATION OF NEW YORK.

METHOD OF SEALING GLASS BULBS.

1,328,530.

Specification of Letters Patent. Patented Jan. 20, 1920.

Original application filed July 3, 1912. Serial No. 707,471. Divided and this application filed March 11, 1916. Serial No. 83,681.

To all whom it may concern:

Be it known that I, ALBERT J. LOEPSINGER, of the city and county of Providence and State of Rhode Island, have invented a certain new and useful Method of Sealing Glass Bulbs; and I do hereby declare the following specification, taken in connection with the accompanying drawings, forming a part of the same, to be a full, clear, and exact description thereof.

The present application is a division of my pending application, Serial Number 707,471, filed July 3, 1912. In that application there is set forth a method of preparing glass bulbs or similar frangible vessels for use in automatic sprinklers of that type which embodies in its construction a frangible vessel having expansible contents, and which is caused to be opened by the expansive or explosive force of the contents of such frangible vessel induced by the action of heat.

The method described in said application involves filling the bulb full of a liquid at a desired high temperature, then cooling the bulb and its contents to normal temperature, then introducing gas into the liquid until the solution substantially fills the bulb, then withdrawing a quantity of the solution until the level of the solution is brought down to the level of the liquid before the gas was introduced, and then sealing the bulb.

The present invention relates to the sealing of bulbs which thus contain a gas in solution, and the invention consists in a novel method of sealing such bulbs, which method is illustrated in the accompanying drawings and will be described in connection therewith.

Referring to the drawings, Figure 1 is a sectional view showing the bulb in position for sealing, and Fig. 2 is a sectional view showing the bulb after it has been sealed.

The frangible vessel comprises a bulb 1 of glass or similar material provided with an elongated neck 2. It is to be understood that this bulb is filled with a gas solution up to the dotted line 3—3 and is ready to be sealed.

The method of sealing the bulb consists in placing the bulb, with the gas solution therein, in a receptacle 4 containing some conducting or heat-absorbing liquid 5, such for example as water or mercury, as shown in Fig. 1, and then applying heat to fuse or close the end of the neck and thus hermetically seal the bulb, as shown in Fig. 2. Preferably the receptacle 5 is provided with suitably shaped holding devices 6—6 to receive and hold the bulb, as shown in Fig. 1.

By thus placing the bulb and its contents in a receptacle containing a conducting or heat-absorbing liquid, the heat applied will be taken up by the surrounding liquid in the receptacle fast enough to prevent the escape of any material quantity of the gas from the bulb during the process of sealing.

What I claim as my invention and desire to secure by Letters Patent is:

1. The method of sealing glass bulbs containing a gas in solution which consists in placing the bulb in a receptacle containing a conducting material and then fusing said bulb.

2. The method of sealing a glass bulb provided with an elongated neck and containing a gas in solution up to a certain point in said neck which consists in placing the bulb in a receptacle containing a conducting material and then fusing the end of said neck.

ALBERT J. LOEPSINGER.
